[57] CLAIM

The ornamental design for an electrically-operated massage appliance, as shown.

DESCRIPTION

FIG. 1 is a front elevational view of the electrically-operated massage appliance showing my new design; FIG. 2 is an elevational view of one side of the appliance, the other side being a mirror image thereof; FIG. 3 is an enlarged bottom plan view thereof; FIG. 4 is an enlarged perspective view of one of the massage fingers, shown separately for ease of illustration; FIG. 5 is a rear elevational view thereof; and FIG. 6 is a top plan view thereof.
